(57) **CLAIM**

The ornamental design for a hand rail, as shown and described.

DESCRIPTION

FIG. 1 is a front right perspective view of the hand rail of the present invention;
FIG. 2 is a right view of the embodiment of FIG. 1;
FIG. 3 is a left view of the embodiment of FIG. 1;
FIG. 4 is a front view of the embodiment of FIG. 1;
FIG. 5 is a back view of the embodiment of FIG. 1;
FIG. 6 is a top view of the embodiment of FIG. 1; and,
FIG. 7 is a bottom view of the embodiment of FIG. 1.
The broken lines are for illustrative purposes only and form no part of the claimed design.

1 Claim, 4 Drawing Sheets

FIG. 6

FIG. 7
